UNITED STATES PATENT OFFICE.

JOSEPH H. WALSH, OF READING, MASSACHUSETTS, ASSIGNOR TO JOHNS-MANVILLE INCORPORATED, OF NEW YORK, N. Y., A CORPORATION OF NEW YORK.

DRIER.

Application filed May 27, 1921. Serial No. 473,201.

To all whom it may concern:

Be it known that I, JOSEPH H. WALSH, a citizen of the United States of America, and resident of Reading, in the county of Middlesex and State of Massachusetts, have invented new and useful Improvements in Driers, of which the following is a specification.

Machines heretofore provided for drying materials continuously passed through a drying chamber have been inefficient and unsatisfactory in many ways. Usually the air in the drying chamber has been merely agitated or churned, to the exclusion of efficient circulation of the heated fresh air within the drying chamber and timely withdrawal of the exhausted or saturated air. Especially in the case of driers for bulk material, such as fibrous stock, grain, rags, wool shoddy, and like materials, the contact of the air with the material has been haphazard and ineffective, particularly in regard to maintaining a sufficient circulation without blowing away the light material. Fumes, steam, odors and dust arising from the material have not usually been prevented from escape into the air of the room where these machines are installed.

One of the objects of this invention it to provide a drier of improved efficiency both as regards distribution of air and conservation of heat, and which will not be subject to the objections mentioned.

A further object is to provide an improved drier for loose material, in which moisture is rapidly removed with a minimum expenditure of heat, and without scattering light materials.

Further objects are to provide a circulating system for driers in which currents of heated air are positively delivered to points where they will be most effective in carrying away the moisture; to provide for screening the educt air in such a way as to avoid loss of fibrous materials, and permit collection of the screenings during the constant operation of the drier; to provide a drier which effectively functions without depending upon convection currents caused by heating units; to avoid heating means in

the drying chamber of the drier, and to provide a drying system having these advantages which may be conveniently applied to installations already in use; and in general to improve the construction and operation, and especially the heat and mechanical efficiency, of machines of the class referred to.

I shall now explain the invention in connection with one embodiment illustrated in the accompanying drawings, for one instance only of a construction comprising the invention, in which,—

Fig. 1 is a front elevation showing a drier of the agitating-table type having mechanically-aided air circulation, the insulating casing being in part removed, the paths followed by the air in the circulating system being indicated by the arrows in the several figures;

Fig. 2 is an end elevation showing the general arrangement of various parts of the drier, and

Fig. 3 is a top plan view of the machine, showing parts in horizontal section.

The invention is applicable to drying machines (by which I refer to the means for circulating or suspending the material to be dried in a drying chamber, and means for confining a quantity of heated or dried air in contact with the material) of many different types, but I have chosen to show herein, for illustration of one specific application, a drier of the agitating-table type substantially corresponding to the Letters Patent to Mathew F. Kelvin, No. 1,249,771, dated Dec. 11, 1917.

The machine of said patent comprises feeding means, a metallic casing B divided by partition b into a heater chamber and a drying chamber, agitating and conveying means in the drying chamber, and a number of blast fans for blowing air from the heater into the drying chamber, through openings in the upper part of wall b.

In general, the drier herein shown utilizes the heating chamber 12 and drying chamber 6 of the prior device, but economically conserves heat and mechanical energy by providing means for causing the entering air to be heated by the educt air, by causing positive circulation and distribution of

heated air throughout the drier, by preventing radiation and convection losses of heat, and by applying the dry, hot air to the work in a new and better way, and by simplifying the circulating means.

The drier as a whole is enclosed by a heat-insulating casing A, Fig. 3, which may comprise suitable supports or standards 1 and asbestos-wood sheet panels 2 secured to opposite sides thereof, and covering the top of the machine, Fig. 1. If desired, the space between the sheets 2 may contain suitable additional heat insulating material, such for example as the corrugated or air-cell asbestos material 3, or other efficient heat insulating packing. The asbestos-wood surfaces are not subject to deterioration by acid fumes or gases destructive of metals. The metal parts may be covered with any suitable fume-resisting coating when the material to be worked upon gives off corrosive fumes. The exterior casing A may be relied upon to prevent seepage of dust or fume-contaminated air into the work-room, and greatly to conserve the reduced amount of heat employed in chamber 12. In some cases the metallic casing B may be dispensed with, the machine parts being erected directly on the walls of the insulating casing A and a suitable partition of similar construction replacing the metal partition b.

The drying machine when employed for drying loose material such as wool, tan-bark, shavings, jute, cotton, rags, or other such materials, is provided with means for feeding, agitating, spreading and advancing the material in a stream through the drying chamber, for example the means shown in said Patent No. 1,249,171, which may be consulted for details of construction. In general, this machine comprises an automatic hopper feeder F and a plurality of tables arranged one above the other, each table comprising a reciprocating member 16, 17 and 18, Fig. 1, which members carry angularly arranged, preferably perforated shelves 19, which shelves cooperate with other angularly arranged stationary shelves 20, whereby the material, fed to one end 21 of the upper table through the hopper 22 by means of a suitable feed-lattice 23 and feed roller 24, is progressively moved throughout the length of the upper table, after which it is delivered to one end of the middle table 17 which moves the material in a direction opposite to the upper table, and delivers to the bottom table 18, and out of the machine toward the right, Figs. 1 and 3.

Whatever the construction of the mechanical parts by which the material is moved through the drying chamber, such as 6, the improved machine includes improved means for delivering upon and circulating through the material air heated in

the heater chamber 12. The chamber 12 is preferably put under a positive air-pressure for this purpose, and passages leading from this chamber are contrived to deliver dry, fresh air adjacent to all parts of the stream of material traveling through the drier. In the preferred arrangement, provision is made for common ascent in chamber 6 of the introduced dry air and the flow of currents of moisture-laden, and therefore lighter, contained air, in opposition to motion of the material downward from level to level of the tables 16, 17, 18 within the chamber 6.

A series of elongated conical tubes 25 communicating with chamber 12 through holes in partitions b and having delivery orifices along their upper sides, is arranged below and adjacent to each of the reciprocating tables, so that the heated air may be conducted from chamber 12 to points adjacent the under sides of the tables 16, 17, 18 and the material to be dried. The heated air may be emitted from the tubes through any suitable openings, but preferably, the orifices are slots provided in the upper side of the tube for this purpose, the width of each slot varying inversely to the corresponding pressure throughout the length of the tube. The material throughout its path in chamber 6 will thus be subjected to uniform streams of dry air from the heater 12 flowing upwardly in the same direction as the flotation currents in the dead air in chamber 6.

The lowermost series of tubes 25 will deliver air, in a current regulated by blast means presently referred to, upwardly through and upon the lower stream of material on table 18. This part of the material has been primarily subjected to the similar impingement of dry warm air from the upper tubes, taking place in an atmosphere of the more humid air which has absorbed the moisture from the lower, upper and intermediate tables of the machine. The drying is thus progressively effected by air having a larger capacity for absorption as the material moves through the machine. But this is effected without creating anywhere in the drying chamber a current having high velocity or great volume, which might carry with it flocculent or light parts of the material, or any current sweeping the planes of the tables and parallel with them, which would be peculiarly adapted to pick up loose particles. So far as the material is blown upon by the air jets, these act upwardly, and through the interstices and perforations of the agitating tables. By these arrangements, the material may be brought into contact with a great volume of air in a minimum of time, without blowing the material about or causing to be taken out of the drier any substantial

amount of the lighter fibres or particles borne by the educt current.

It is desirable to provide means for preventing the small amount of the loose material inevitably borne by the air from being carried off through the educt air channels. For this purpose, there is provided a screen 7 arranged accessibly for replacement across the intake end of the educt passage 30 from chamber 6 into a pre-heater chamber 8 presently referred to. When the screen becomes coated or clogged, the screen may readily be removed and replaced by a cleaned screen through a door 31 in casing A without causing interruption of the operation of the machine.

The heat supplied to the system by the steam coil 13 in the chamber 12 is largely conserved by the prevention of radiation losses and the complete enclosure of the drying chamber, but a large quantity of heat remains in the educt moist air from the drying chamber 6. Driers corresponding to the invention cannot be operated so that the supply of heated and dry air is exactly proportioned to the moisture to be evaporated. Excess of heat is often required, or the charge flowing through the machine may vary in quantity or in proportion of contained moisture.

This invention utilizes the heat heretofore wasted remaining at the educt from the drying chamber to pre-heat the entering air and thus lessens the amount of heat required to be radiated by coil 13, which may be correspondingly reduced in size and consumption of steam avoided. The incoming and outgoing air-currents are so arranged as to permit by conduction through confining walls separating them and radiation therefrom, an interchange of heat without mixture of the currents of air or interchange of the contained moisture of the educt current. For this purpose, the entering and leaving air-currents are taken through a pre-heater or regenerating unit 8 comprising a chamber of the casing A preferably placed on top of the drying chamber 6.

The pre-heater or regenerating unit may comprise a plurality of passages, shown as tubes 35, having metallic or other conducting walls adapted for radiation, each having one end communicating with an outlet or exhaust passage 36, and its other end opening into educt passage 30 of the drying chamber 6. The heated air from the drying chamber passes through the tubes 35 and into the exhaust or outlet passage 36, and during this passage gives up most of its heat to air entering the system. The pre-heater tubes are contained within chamber 8, which may be provided with baffles 38 adapted to support the tubes 35 and determine a sinuous path for air taken into

the system leading into repeated contact with the tubes 35. Air enters through an inlet pipe 10 leading into the top of casing A and into chamber 8, at one end of said sinuous path, the other end of the path 70 marked off by the baffles communicating through a pipe 38 with a suitable fan 11 adapted to force the pre-heated air into the heater chamber 12 containing the heater coils 13.

What I claim is:

1. A drier having therein, in combination, heating means and a drying chamber communicating therewith, an induct passage for air and a plurality of educt passages leading from the drying chamber separated by walls adapted to radiate to the entering air heat acquired from the educt air, and means for maintaining a positive air pressure in said heating means to circulate air through 85 said chambers and passages.

2. A drier having therein, in combination, a heat-insulating enclosure, heating means, and a drying chamber communicating therewith within said enclosure, an induct passage for air and a plurality of educt passages leading from the drying chamber separated by walls adapted to radiate to the entering air heat acquired from the educt air, and means for maintaining a positive 95 air pressure in said heating means to circulate air through said chambers and passages.

3. A drier for materials in bulk having therein a drying chamber and means for 100 moving the material through the chamber in a stream, means for delivering into contact with the material at a plurality of points along said stream blasts of heated dry air, and means whereby air rendered 105 moist by contact with the material is caused to flow from the drying chamber.

4. A drier for materials in bulk having therein a drying chamber and means for moving the material through the chamber 110 in a stream, means for agitating the material during its progress, means for delivering into contact with the material at a plurality of points along said stream blasts of heated dry air, and means whereby air 115 rendered moist by contact with the material is caused to flow from the drying chamber at a point near the entering run of the stream of material.

5. A drier for materials in bulk having 120 therein a drying chamber and means for moving the material through said chamber in a stream, a heating chamber, and means for maintaining a circulation of air through said chambers comprising means for delivering 125 from the heating chamber to the drying chamber a number of upwardly directed substantially uniform blasts of heated dry air.

6. A drier for materials in bulk having 130

- 4
- therein a drying chamber and means for moving the material through said chamber in a stream, a heating chamber, means for maintaining a circulation of air through said chambers comprising means for delivering from the heating chamber to the drying chamber a number of upwardly directed substantially uniform blasts of heated dry air, and means for permitting flow of air from the drying chamber at a point above the stream of material.
7. A drier for materials in bulk having therein a drying chamber and means for moving the material through said chamber in a stream moving from height to height within said chamber, the material entering said chamber at the upper run of said stream, a heating chamber, and means for maintaining a circulation of air through said chambers comprising means for delivering from the heating chamber to the drying chamber at points distributed throughout the length of said stream, a number of upwardly directed substantially uniform blasts of heated dry air.
8. In a drier of the agitating-table type, in combination, with the means for agitating and advancing the material in a closed chamber, means for delivering against the underside of the stream of material a number of relatively uniform blasts of air, comprising a plenum chamber, and a number of air-delivering tubes having upwardly directed orifices and extending from the plenum chamber into the spaces under the agitating tables.
9. A drier having therein, in combination, a drying chamber and air educt means therefor, means for moving material to be dried through the drying chamber, a heating chamber and air induct means therefor communicating passages between said chambers, a heat interchange pre-heater including said educt and induct means, and means between said pre-heater and said heating chamber for maintaining a positive air-pressure in said heating chamber.
10. A drier having therein in combination, a drying chamber having air inlet tubes arranged at different levels therein and an outlet at the top thereof, and means for carrying the material to be dried successively above the respective air inlet tubes, the means for carrying the material causing it to travel from the top towards the bottom of the chamber, whereby the material is successively subjected to independent air currents from said tubes acting in an atmosphere progressively increasing in absorbent capacity.
11. In a drier, in combination with an air-heating and a drying chamber, a heat regenerator arranged above the drying chamber, said regenerator having passages communicating with an outlet from the drying chamber fresh air induct means providing a passage in contact with walls of the heat regenerator outlet passages for pre-heating the fresh air entered, connections between said fresh air passages of the regenerator and the heating chamber, and means for causing a positive circulation of air through the said chambers, passages and connections.
12. In a drier, in combination with an air-heating and a drying chamber, a heat regenerator arranged above the drying chamber, said regenerator having passages communicating with an outlet from the drying chamber, a removable screen arranged between the drying chamber and the heat regenerator, fresh air induct means providing a passage in contact with walls of the heat regenerator outlet passages for pre-heating the fresh air entered, connections between said fresh air passages of the regenerator and the heating chamber, and means for causing a positive circulation of air through the said chambers, passages and connections.
13. A drier of the agitating-table type for drying loose material, comprising, in combination, a drying chamber, agitating tables therein, a heat regenerator communicating therewith, a removable screen arranged between the drying chamber and the regenerator, and means for removing air from the drying chamber through said screen and regenerator.
14. In a drier, in combination with a heat insulating casing, chambers within the casing respectively for means for moving the material to be dried into, through, and out of contact with dry air, said chamber having an air educt passage; for means for heating the air, said chamber having an air-inlet passage; and for a radiating surface separating the air-educt passage from the drying chamber and the air-inlet passage.
15. In a drier, in combination with a heat insulating casing, chambers side by side within the casing respectively for means for moving the material to be dried into, through, and out of contact with dry air, and for means for heating the air; and a chamber above one of said chambers and within said casing having therein a radiating surface separating an air-educt passage from the drying chamber, and an air-inlet for the heating chamber.
16. In a heat-interchange pre-heater for driers, the combination with an insulating casing of a number of exhaust-air outlet tubes in parallel relation, baffles supporting the tubes and providing a sinuous passage about them, inlet and outlet opening at each end of said sinuous passage and said exhaust-air tubes respectively, and suitable connections therefrom respectively to the educt and induct air passage of the drier.
17. In a drier, in combination with a dry-

ing chamber and means for feeding a stream of light material from level to level therein, means for moving the contained air of said chamber and withdrawing the saturated or exhausted air comprising means for causing the incoming air and outgoing air to flow through the planes of said levels, whereby to

avoid currents along or across said levels and prevent substantial air-borne portage of the material.

10

Signed by me at Boston, Massachusetts, this twenty-fourth day of May, 1921.

JOSEPH H. WALSH.
